Des. 211,513
Patented June 25, 1968

211,513

EGG TRAY

Thomas E. Brown, Slatersville, and James B. Swett, Barrington, R.I., assignors to Rexall Drug and Chemical Company, Los Angeles, Calif.

Filed Nov. 2, 1966, Ser. No. 4,511

Term of patent 14 years

(Cl. D9—190)

FIG. 1

FIG. 2

FIG. 3

FIG. 4

FIG. 5

FIG. 6

FIG. 7

FIGURE 1 is a perspective view of an egg tray showing our new design;

FIGURE 2 is a cross-sectional view taken on line 2—2 of FIG. 1;

FIGURE 3 is a side elevational view thereof;

FIGURE 4 is an enlarged end elevational view thereof;

FIGURE 5 is an enlarged cross-sectional view taken on line 5—5 of FIG. 1;

FIGURE 6 is an enlarged cross-sectional view taken on line 6—6 of FIG. 1; and

FIGURE 7 is a plan view thereof.

We claim:

The ornamental design for an egg tray, as shown.
